(57) **CLAIM**

The ornamental design for a handle of toilet brush, as shown and described.

DESCRIPTION

FIG. 1 is a front and right side perspective view of a handle of toilet brush showing my new design;
 FIG. 2 is a back and left side perspective view thereof;
 FIG. 3 is a front elevation view thereof;
 FIG. 4 is a back elevation view thereof;
 FIG. 5 is a left side elevation view thereof;
 FIG. 6 is a right side elevation view thereof;
 FIG. 7 is a magnified top plan view thereof;
 FIG. 8 is a magnified bottom plan view thereof;
 FIG. 9 is a partial enlarged view of FIG. 1;
 FIG. 10 is a partial enlarged view of FIG. 2; and,
 FIG. 11 is a partial enlarged view of FIG. 5 thereof.

Environmental subject matter is illustrated with broken lines in FIG. 7. The broken lines in FIGS. 1-2, and 5 illustrate the indicia for the enlarged drawings that are taken from these figures. The broken lines in FIGS. 9-11 illustrate the bounds of the enlargements. None of the elements shown in broken lines forms a part of the claimed design.
